UNITED STATES PATENT OFFICE.

ALEXANDRE F. GODEFROY, OF ST. LOUIS, MISSOURI.

HAIR-DRESSING DEVICE.

SPECIFICATION forming part of Letters Patent No. 389,803, dated September 18, 1888.

Application filed April 13, 1888. Serial No. 270,543. (No model.)

To all whom it may concern:

Be it known that I, ALEXANDRE F. GODEFROY, of the city of St. Louis, in the State of Missouri, have invented a certain new and useful Improvement in Hair-Dressing Devices, of which the following is a full, clear, and exact description, reference being had to the accompanying drawings, forming a part of this specification, and in which—

10 Figure I is a perspective view illustrative of my invention. Fig. II is a similar view showing the heater removed. Fig. III is a detail section, this section being taken on line III III, Fig. II. Fig. IV is a bottom view.

15 My invention relates to a device for dressing the hair; and it consists in features of novelty hereinafter fully described, and pointed out in the claims.

Referring to the drawings, 1 represents a 20 case or box, forming a chamber, 2. This case or box has a flexible front portion, 3, which has an opening, 4, to fit the head, as shown in Figs. I, II, and IV. The lower part of this flexible piece is extended to form an imperforate drip-apron, 5.

25 When the device is used for shampooing, for instance, the part 1 of the case is removed from the part 3, and the water and suds pass down the apron 5 and are discharged, as shown in Fig. II, at the lower end of the apron. Then, when the device is to be used for drying the hair, the part 1 of the case is applied and is connected by means of a pipe, 6, to any suitable form of heater, 7. The heat is discharged 35 into the chamber 2, escaping through a pipe or flue, 8, on top of the case, and drying the hair as it passes through the chamber.

Still another use to which the device may be applied is that of shaping wig-holders.

The pipe 6 of the furnace 7 may be provided with branches 20, connecting the pipe to the sides and bottom of the part 1 of the case, for the purpose of discharging heat at different points, and these branches may be provided with valves 21, to regulate the quantity of heat 45 entering the chamber 2.

I claim as my invention—

1. In a hair-dressing apparatus, the combination of a case having a flexible portion to fit the head, and a furnace for discharging heat 50 into the case, substantially as set forth.

2. In a hair-dressing apparatus, the combination of a case having a flexible portion to fit the head, and a furnace provided with a pipe, and branches having valves for communicating with the case and discharging heat into 55 the case, substantially as and for the purpose set forth.

3. In a hair-dressing apparatus, the case having a flexible portion to fit the head, and an imperforate apron, 5, wherefrom the water and suds escape at its rear edge, substantially as and for the purpose set forth.

4. In a hair-dresser, the case having a flexible portion, 3, to fit the head, and a removable portion, 1, the portion 3 having an apron, 5, substantially as and for the purpose set forth.

ALEXANDRE F. GODEFROY.

In presence of—
GEO. H. KNIGHT,
JOS. WAHLE.
